UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

OPEN-TOP DRIER.

Application filed October 19, 1927. Serial No. 227,232.

My present invention relates to brick making machines, and more particularly to an improved drier for bricks and the like.

In my copending application, Serial No. 5 227,231, filed Oct. 19, 1928, I have described and claimed an improved method of manufacturing brick by the soft mud process, wherein the loaded pallets are collected in groups and placed in a container and which 10 container is placed in a drier of the open top variety, where the bricks on the pallets are subjected to a preliminary drying operation prior to being built into unit stacks for forming a kiln. As in the prior art, there was no 15 satisfactory open top drier which could be advantageously utilized in connection with my improved method, as set out in the application above referred to, I have designed the drier forming the subject matter of the present invention. In this drier I have utilized 20 to the greatest extent possible the exhaust heat from a battery of boilers, as well as utilizing heat from steam generated by such boilers. By thus utilizing direct heat and 25 the exhaust heat, I obtain the greatest efficiency from whatever fuel is utilized under the boilers and reduce the cost of drying bricks to a minimum. In designing this open top drier, I have provided therein a plurality 30 of parallelly arranged compartments, in each of which is arranged a heating coil, preferably located at the bottom thereof, and at one end of each of the parallelly arranged compartments, I provide an air inlet which 35 conducts the waste heat from the battery of boilers into the compartment and at the other end of the compartment I provide an outlet for such exhaust heat and connect the heated air inlet chamber with the source of exhaust 40 heat by means of an inlet fan and connect the heated air outlet chamber with the outer atmosphere by means of an exhaust fan. By this means, therefore, I am enabled to create 45 a positive flow of heated air through the compartments. Each compartment is built of a size to readily accommodate a container such as is disclosed and claimed in my copending application, Serial No. 227,231, filed Oct. 19, 1928, and each container has associated therewith at its top end a top of heat 50 insulating material. Therefore, as each container is placed in a compartment of the open top drier forming the subject matter of the present invention, that portion of the open top drier is practically sealed against the

exit of air, and when the compartment is filled with containers, such compartment is practically closed and air can issue therefrom only from the air outlet leading to the air outlet chamber.

The object of my invention, therefore, is an improved open top drier.

In the accompanying drawings illustrating a preferred embodiment of my invention,

Fig. 1 is a plan view;

Fig. 2 is a sectional end elevation on the line 2—2 of Fig. 1, and

Fig. 3 is a sectional elevation on the line 3—3 of Fig. 1.

Referring to the drawings, 10 designates a concrete base provided with a centrally arranged trough or grooves 11 extending throughout the length thereof. Erected on and formed integral with the base 10, while spaced apart from and parallel to each other, are side walls 12 and 13 of any suitable length, height and thickness. Extending between the side walls 12 and 13 parallel to and spaced apart from each other, are transverse walls 14, such walls, together with the side walls 12 and 13, defining a plurality of compartments 15. These compartments are of a width to readily receive a container 16 loaded with pallets 17 and with each pallet having thereon a plurality of parallelly arranged brick 18 and the height of the walls 14 is greater than the length of a container 16. Each wall 14 is capped with a channel iron or other suitable member 19.

Referring to Fig. 3, it will be noted that 90 the containers 16 are provided at the top end with a top portion 20 which rests on the caps 19 and practically suspends the container 16 within its respective compartment 15. Therefore, as the top 20 may be of suitable insulating material, it is obvious that the relatively great weight of the container, with its load of pallets 17 and 18 respectively, will tend to make a tight joint between the top 20 and the caps 19. The compartments 14 are of 100 a length to receive a plurality of containers 16, as will be seen from an inspection of Fig. 2 and, therefore, when a compartment 14 is filled with containers 16, it is substantially a closed chamber except for any openings that 105 may be purposely made therein and which will be hereafter described.

At the end of the plurality of compartments 15 and on the concrete base 10 are arranged a battery of boilers 21, provided with 110

means 22 at the flue end thereof for collecting the heat from the spent gases and which means 22 is connected to an inlet fan 23. The inlet fan 23 is driven by belt 24 from a motor 25 or from any other suitable source of power and such inlet fan 23 connects with one end of an air inlet chamber 26 formed of a side wall 27 arranged parallel to but spaced apart from the side wall 12 and closed 10 by a top 28, such sides and the top 28 being preferably of heat insulating material. At the lower portion of the side wall 12 and connecting each compartment 15 with the air inlet chamber 26 is a passage 29 and through which 15 heated air from the inlet fan 23 passes from the air inlet chamber 26. Erected on top of the concrete base parallel to but spaced apart from the side wall 13 is a wall 30 and resting on top of the wall 30 and connected to the 20 side wall 13 is a top 31, the side wall 30 and top 31 being preferably of heat insulating material. The side wall 13, wall 30 and top 31 define an air outlet chamber 32, which is closed at one end and at the other end is connected to an exhaust fan 33 that is driven by belt 34 from a motor 35 or from any other suitable source of power. The side wall 13 adjacent to the under side of the top 31 is provided with a plurality of passages 36, which 25 connect the individual compartments 15 with the air inlet chamber 32. Any air handled by the exhaust fan 33 will be taken from the air inlet chamber 32 and any air in the air inlet chamber 32 must come from the compartments 15 through the passages 36.

By reference to Fig. 2, therefore, it will be noted that heated air entering the compartments 15 through the passages 29 will take a general movement lengthwise and upward 40 of the compartments 15 and will pass out through the passages 36 into the air outlet chamber 32. The battery of boilers 21 are utilized to generate steam for the brick plant engine or engines and the exhaust steam from 45 such engine or engines is conducted into a steam inlet pipe 37 lying in the trough 11 and this steam pipe 37 has connected thereto at intervals along the length thereof steam coils 38, there being one of such coils in each 50 of the compartments 15. Each coil 38 is also connected to an outlet pipe 39, leading to the outer atmosphere or to a condenser, as may be

desired. The apparatus is provided with means for connecting each individual heating coil 38 to the steam pipe 37 at will and as each compartment 15 is filled, the heat is turned into the heating coil 38 associated with the compartment. As the containers 16 are loaded into a compartment 15, and such compartment filled, heated air through the associated passage 29 is allowed to be forced into such compartment by the inlet fan 23 and to be drawn out therefrom through the associated passage 36 into the air outlet chamber 32 by the exhaust fan 33. Simultaneously, heat is turned into the associated heating coil 38, and, therefore, it will be obvious that the brick 18 contained on the pallets 17 of the plurality of containers 16 in the particular compartment 15 is subjected to an intense drying operation. Also, as the compartments 15 are relatively small, and the holding capacity therefore relatively small, they are rapidly filled and, therefore, the drying operation takes place on the brick 75 within a comparatively short time after such brick are molded. It is possible, therefore, with the present device to perform the drying operation practically as a continuous proposition rather than as a batch proposition, such as had to be done heretofore where the drier was of a character to contain practically a day's output of the brick-making machine.

Having thus described my invention, what I claim as new is:

In an open top drier of the kind described, the combination of a base, a plurality of parallelly arranged compartments formed on the top thereof, an air inlet chamber arranged at one end of each of the compartments and being connected to each of said compartments, an air outlet chamber arranged along the other end of said compartments and being connected to each of said compartments, 90 a heating coil arranged in the bottom of each compartment, said compartments being adapted to be filled with a plurality of containers, which containers form a top for the drier.

In testimony whereof, I have signed my name to this specification.

CLAUD E. FULLER.
